The ornamental design for a set of nested measuring cups, as shown and described.

DESCRIPTION

FIG. 1 is a perspective view of a set of nested measuring cups showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is an exploded perspective view of the set of nested measuring cups shown in FIG. 1;
FIG. 9 is a perspective view of a first measuring cup of the set of nested measuring cups of FIG. 1, shown with the other measuring cups removed for ease of illustration;
FIG. 10 is a front elevational view thereof;
FIG. 11 is a rear elevational view thereof;
FIG. 12 is a left-side elevational view thereof;
FIG. 13 is a right-side elevational view thereof;
FIG. 14 is a top plan view thereof;
FIG. 15 is a bottom plan view thereof;
FIG. 16 is a perspective view of a second measuring cup of the set of nested measuring cups of FIG. 1, shown with the other measuring cups removed for ease of illustration;
FIG. 17 is a front elevational view thereof;
FIG. 18 is a rear elevational view thereof;
FIG. 19 is a left-side elevational view thereof;
FIG. 20 is a right-side elevational view thereof;
FIG. 21 is a top plan view thereof;
FIG. 22 is a bottom plan view thereof;
FIG. 23 is a perspective view of a third measuring cup of the set of nested measuring cups of FIG. 1, shown with the other measuring cups removed for ease of illustration;
FIG. 24 is a front elevational view thereof;
FIG. 25 is a rear elevational view thereof;
FIG. 26 is a left-side elevational view thereof;
FIG. 27 is a right-side elevational view thereof;
FIG. 28 is a top plan view thereof;
FIG. 29 is a bottom plan view thereof;
FIG. 30 is a perspective view of a fourth measuring cup of the set of nested measuring cups of FIG. 1, shown with the other measuring cups removed for ease of illustration;
FIG. 31 is a front elevational view thereof;
FIG. 32 is a rear elevational view thereof;
FIG. 33 is a left-side elevational view thereof;
FIG. 34 is a right-side elevational view thereof;
FIG. 35 is a top plan view thereof;

FIG. 36 is a bottom plan view thereof;
FIG. 37 is a perspective view of a fifth measuring cup of the set of nested measuring cups of FIG. 1, shown with the other measuring cups removed for ease of illustration;
FIG. 38 is a front elevational view thereof;
FIG. 39 is a rear elevational view thereof;
FIG. 40 is a left-side elevational view thereof;
FIG. 41 is a right-side elevational view thereof;
FIG. 42 is a top plan view thereof;
FIG. 43 is a bottom plan view thereof;
FIG. 44 is a perspective view of a sixth measuring cup of the set of nested measuring cups of FIG. 1, shown with the other measuring cups removed for ease of illustration;
FIG. 45 is a front elevational view thereof;
FIG. 46 is a rear elevational view thereof;
FIG. 47 is a left-side elevational view thereof;
FIG. 48 is a right-side elevational view thereof;
FIG. 49 is a top plan view thereof;
FIG. 50 is a bottom plan view thereof;
FIG. 51 is a perspective view of a seventh measuring cup of the set of nested measuring cups of FIG. 1, shown with the other measuring cups removed for ease of illustration;
FIG. 52 is a front elevational view thereof;
FIG. 53 is a rear elevational view thereof;
FIG. 54 is a left-side elevational view thereof;
FIG. 55 is a right-side elevational view thereof;
FIG. 56 is a top plan view thereof; and,
FIG. 57 is a bottom plan view thereof.

The broken lines formed by short dashes showing the units of measurement and the locking mechanism in FIGS. 1-57 represent portions of the set of nested measuring cups that form no part of the claimed design. The broken lines formed by alternating short dashes and long dashes and faded portions within in FIGS. 2, 3, 6, 14, 21, 28, 35, 39, 45, and 52 represent boundaries of the set of nested measuring cups that form no part of the claimed design.
